UNITED STATES PATENT OFFICE.

ROBERT F. HUDSON, OF RICHMOND, VIRGINIA.

TRAIN-CONTROL SYSTEM.

1,387,400.

Specification of Letters Patent.

Patented Aug. 9, 1921.

Application filed October 27, 1919. Serial No. 333,784.

To all whom it may concern:

Be it known that I, ROBERT F. HUDSON, a citizen of the United States, residing at Richmond, in the county of Henrico and

5 State of Virginia, have invented certain new and useful Improvements in Train-Control Systems, of which the following is a specification, reference being had therein to the accompanying drawing.

10 This invention relates to improvements in train control systems, one object of the invention being the provision of a novel arrangement of ramp and ramp engaging mechanism whereby the source of energy is carried upon the moving vehicle and a closed 15 circuit is maintained at all times so as to cause no case of an open circuit and stop condition.

20 A further object of this invention is the provision of a novel arrangement of a ramp and ramp contact whereby a rail section of extreme shortness is used and one which is readily installed and easily up-kept.

25 A still further object of this invention is the provision of means whereby a plurality of ramps are connected in such a manner that the signal when at danger will affect one ramp so as to produce a retardation of speed, a second ramp so as to produce a further retardation and a third ramp so as to bring the train to a halt, this giving a tapered or application stopping effect instead of venting suddenly the entire system and causing damage to the rolling stock.

30 In the accompanying drawings:

Figure 1 is a top plan view of several blocks in a railway system equipped according to and embodying the present invention.

Fig. 2 is a side elevation of a locomotive 40 and the traffic rail adjacent a ramp.

Fig. 3 is an enlarged diagrammatic view of the train carried circuit and also showing a ramp rail adjacent thereto.

Fig. 4 is an enlarged detail sectional view 45 through the ramp rail and through one of the contact members, the contact member being shown in engagement with the ramp rail.

Fig. 5 is a top plan view of the ramp rail, 50 dotted line showing the relative positions of the flanged wheels of a locomotive and the driving wheels when passing that point.

Referring to the drawings, the numeral 10 designates the track battery and 11 the 55 track relay, which has under its influence an armature 12 which is connected by means

of the conductor *a* and contact *b* to the track rail 14 and to the ramp rails 16 and 16' through the conductors 15 and 15' respectively.

60 This ramp rail 16 or 16' is in practice to be from four to twelve feet long and is so positioned that the upper or contact edge 17 thereof will be slightly above and spaced from the wheel engaging portion of the rail, 65 the blocks 18 of insulation being so disposed as to permit the snow and ice and water to pass therethrough without any tendency to short circuits or bridging.

70 This ramp rail is so constructed and arranged as to not be engaged by the flanged wheels of the locomotive and train but to be ridden by the driving wheels, this action by the driving wheels removing all frost and snow and ice that would adhere and thus 75 insure a perfect contact for the shoe member, as will presently appear.

75 The shoe member is preferably carried by the tender of the locomotive as shown in Fig. 2 and comprises a supporting frame 80 19 having the auxiliary frame 20 which forms a support for the two shafts or spindles 21 of the spring projected caster frames 22, carrying the respective contact wheels 23, two of these being preferably employed. 85 It will be noticed that each of the wheels 23 in cross section has its contact surface tapered, this being to permit of the same engaging the contact surface 17 of the ramp rail, as shown in Fig. 4, which in turn elevates the balance of the surface of the contact wheel from the traffic rail, in this shifting the current flow from the locomotive circuit to and through the contacts 13 and 15 and the stick relay 12.

90 95 The apparatus carried upon the locomotive includes the battery 25 which is connected at one side to both of the ramp engaging members 21, while on the opposite side the conductor 26 is led to the cab relay 27, 100 here shown as of a solenoid type, the conductor 28 being connected to the opposite side and led through the switch 29 where it is grounded to the locomotive and consequently to the traffic rail. Thus when the contacts 23 are engaging the traffic rail a circuit to the solenoid 27 is closed, while the shunt connection through the conductors 30 and 31 and the switch 29 maintains the clear 105 light or lamp 32 energized.

110 When contacts 23 ride upon the frame and the stick relay 12 is operated upon the

track relay 11, the current continues to flow to energize the solenoid 27 but is shunted through the ramp 16, stick armature 12, back to the traffic rail through the conductor 13. If on the other hand the track relay 11 is deenergized and the stick relay 12 is open, the circuit to the solenoid 27 and the light 37 will be opened and the lever 33 operated by the solenoid will in turn lower 10 and open the switch 29 so that even upon the contacts leaving the ramp and engaging the track relay, the circuit will remain open and the train be brought to a halt due to the venting of the train line through the valve 34 operated by the lever 33.

This valve is indicative of any form of means for venting the train pipe but it is desirable that such pipe be connected so as to prevent the engineman from taking control of the train, that is, it must be connected to prevent the air from the main reservoir entering into the train line pipe until the train is brought to a full stop and sufficient time has elapsed to permit the trainman to take charge.

It is also possible to use in conjunction with this system a speed circuit control device which will permit the engineman to take charge of the train and proceed at a reduced 30 rate until he enters a safety zone. In this form of apparatus it will be seen that the ramp being an exceedingly short member it is readily installed on the railroads in an easier and cheaper manner and maintained 35 at the smallest outlay, the battery and all other apparatus being carried upon the locomotive and necessitating no testing at the ramps to ascertain the workability of the system.

40 By using two contact wheels 23 it is absolutely sure that proper connection will be made in rounding curves and other places, as one wheel will check on the other.

Two ramps, 16 and 16' are here shown 45 although not absolutely necessary but insure

the positive actuation of the present device as each ramp has the same effect as the other, therefore, when the ramp 16' is engaged it may not be sufficiently long to produce the desired action on the vehicle, so 50 that by the time the ramp 16 is engaged the vehicle will be brought under control either in caution or danger to a slow-down or stop. If desired, additional ramps may be employed in a similar manner.

55 What I claim as new is:

1. In a train control system, the combination with traffic rails divided into blocks, a ramp rail disposed parallel to and spaced from one of said rails, the tread surface 60 thereof being disposed slightly above the contact surface of the traffic rail, and a contact shoe carried by a moving vehicle and including a surface for normally engaging the traffic rail and which when in engagement with the ramp rail will be out of contact with the traffic rail.

2. The combination with a short ramp rail the contact surface of which is spaced from and slightly above the contact surface of 70 the traffic rail, of a shoe including a contact surface disposed to normally engage the traffic rail but which when engaging the ramp rail is elevated above and held out of contact with the traffic rail.

75 3. The combination with a vehicle having controlling mechanism for regulating the speed thereof, of means carried by the vehicle and along the right of way for actuating said controlling means, said latter co-operating means comprising a ramp rail and a traffic rail, the upper surface of the ramp rail being spaced from and slightly above the traffic rail and a vehicle carrying member comprising a contact surface disposed to 80 normally engage the traffic rail and to be held out of contact with the traffic rail when engaging the ramp rail.

85 In testimony whereof I affix my signature.

ROBERT F. HUDSON.
